UNITED STATES PATENT OFFICE.

JAMES T. HAMILTON AND CHARLES C. McMULLEN, OF ELLISVILLE, MISSISSIPPI.

RAILWAY-SWITCH.

1,135,375.

Specification of Letters Patent. Patented Apr. 13, 1915.

Application filed July 6, 1894. Serial No. 849 131.

To all whom it may concern:

Be it known that we, JAMES T. HAMILTON and CHARLES C. McMULLEN, citizens of the United States, residing at Ellisville, in the county of Jones and State of Mississippi, have invented certain new and useful Improvements in Railway-Switches; and we do declare the following to be a full, clear, and exact description of the invention, such as will enable others skilled in the art to which it appertains to make and use the same.

Our invention relates to improvements in railway switches and has for its primary object to provide simple and efficient means whereby the usual frog may be dispensed with.

A secondary object of the invention is to construct the device in such a manner as to allow both the main line and siding to have practically solid rails.

In carrying out these objects, we provide a pivoted rail section which is adapted to bridge a gap in one rail of the main line or in one rail of the siding as the case may be.

A further object of the invention is to provide simple and efficient means whereby said pivoted rail section is held against tilting.

30 A still further object is to provide means, carried by said pivoted rail section, for preventing injury to a dragging brake beam.

With these objects in view, our invention resides in certain novel features of construction and combination herein described and claimed and shown in the drawings wherein:

Figure 1 is a plan view of a railway switch constructed in accordance with our invention, the switch being closed; Fig. 2 is a similar view with the switch open; Fig. 3 is a transverse section taken along the plane of the line 3—3 of Fig. 1; Fig. 4 is a similar view taken upon the line 4—4 of Fig. 1; and Fig. 5 is a detail perspective view of a portion of the pivoted rail section, showing more particularly the construction of a guard to be described.

50 In the accompanying drawings, we have

shown our invention as applied to a main track 1 and a siding 2, the former comprising a continuous rail 3 and a rail 4 parallel therewith and having a gap 5 a portion of said track 4 being extended laterally at an angle to provide one rail 6 of the siding 2, the remaining rail 7 of said siding having a gap 8.

By reference to Figs. 1 and 2, it will be seen that the rails 4 and 7 each terminate in a switch tongue 9, said tongues being pivotally connected to an operating rod 10 which may be shifted laterally by any suitable means such as a lever 11. By the construction above set forth, it will be seen that the rails 4 and 7 lie in intersecting planes and that the ends of said rails as well as the adjacent ends of the switch tongues 9 are rigidly secured to a solid base plate 12, the latter being rigidly supported upon certain of the cross ties 13 and having a central bearing recess 14 in its upper portion, said recess being of substantially cone-shape and having a bore 15 passing therefrom through the lower portion of said base plate.

The bearing opening 15 is provided for the reception of a substantially cone-shaped pivot member 16, the latter having a depending shank 17 which is rotatably mounted in the opening 15 and which receives a washer 18 and nut 19 on its lower end. It is to the bearing member 16 that a pivoted rail section 20 is rigidly secured in any suitable manner as by machine bolts 21, said rail section 20 being of sufficient length to entirely bridge the gaps 5 and 8 when swung in the proper direction.

For the purpose of swinging the rail section 20 simultaneously with the switch tongues 9, we provide said section 20 with a laterally extending operating rod 22 which is pivoted at 23 to a rather long arm 24 of a bell crank lever, the latter being pivoted at 25 to one of the ties 13 and having its comparatively short arm 26 extending outwardly from said pivot and pivotally connected at 27 to a longitudinal operating rod 28, the latter being pivoted at 29 to one arm of a bell crank lever 30 which is pivoted to one of the ties 13 and whose remaining arm 16

is pivotally united at 31 to one end of the transverse switch operating bar 10. The proportioning of the parts so far described, is such as to allow the proper movement of 5 the pivoted rail section 20 when the switch tongues 9 are operated by the rod or bar 10.

Although the pivotal support for the rail section 20 provides a rather rigid mounting therefor, we have found it expedient to provide 10 specially constructed means for preventing said section from tilting, said means being in the form of bars 32, a pair of which projects laterally from each end portion of said rail section, the outer ends of said bars 15 being formed into hooks 33 whose bills open inwardly and are adapted to engage the parallel edges of the base plate 12 when the section 20 stands in either one of its adjusted positions. By this means, it will be seen 20 that any possible tilting, on the part of the rail section 20, will be prevented.

As positive means for preventing excessive movement of the pivoted section 20 in either direction, we have provided a number 25 of angular stops 34 which are carried rigidly by the bed plate 12, said stops contacting with the sides of said section and not only acting as stops but serving to still further brace the same against tilting.

30 In connection with the features so far described, we preferably provide a pair of guard rails 35, one of said rails being disposed adjacent the track 3 while one is located directly inside the rail 6 of the siding. 35 It will therefore be seen that lateral shifting on the part of the trucks of a train, is prevented since the wheel flanges of said trucks are limited against lateral or transverse movement by said guard rails, thus 40 preventing undue lateral pressure from being exerted upon the pivoted rail section 20.

From the foregoing description, taken in connection with the accompanying drawings, it will be seen that we have produced 45 an extremely efficient switch yet one which will be highly efficient and positive in operation.

By reference, more particularly to Figs. 1 and 2, it will be seen that the inner ends 50 of the switch tongues 9 as well as the adjacent ends of the rails 4 and 5 are exposed at times. It is a well known fact that brake beams often become loosened from their supports upon rolling stock and are therefore drawn along the rails of the track. If these beams should come in contact with an immovable object, the result would undoubtedly be a severe accident. It is to overcome this difficulty that we have provided 55 the following means whereby a dragging brake beam will be gradually moved upwardly and thus prevented from forcibly striking the ends of the tongues 9 on the adjacent ends of the rails 4 and 5. Said

last mentioned means is here shown in the 65 form of a pair of laterally extending arms 36 which are rigidly secured to the rail section 20 and whose outer ends are deflected in such a manner as to position them adjacent certain of the rail sections when the 70 switch is swung to one position. It will therefore be seen that should a dragging beam come in contact with one of the arms 36, the formation of the latter will accurately raise said beam and allow the same to 75 continue to slide upon the rails of the track. We deem this feature of our invention extremely important since, as above suggested serious accidents may be averted by this simple yet efficient means.

80 We have described our invention with considerable minuteness but we do not wish to be limited to details of construction other than those amplified in the appended claims.

Having thus described our invention what we claim as new and desire to secure by Letters Patent is:—

1. The combination with a pair of rails lying in intersecting planes and having gaps at their point of intersection, of a pivoted 90 rail section pivoted at the intersecting point of said planes and designed to bridge the gaps in said rails, hook-shaped stop members projecting laterally from the opposite ends of said pivoted rail section and means 95 coacting with said hook-shaped stop members for limiting the swinging movement of said pivoted rail section.

2. The combination with a pair of rails lying in intersecting planes and having gaps 100 adjacent their intersecting point, of a rigid bed plate underlying the ends of said rails adjacent the gaps, a rail section pivoted upon the top of the plate to swing in a horizontal plane, means whereby said rail 105 section may be swung around its pivot, and laterally extending bars rigidly secured to the opposite end portions of the pivoted rail section and having their outer ends formed into inwardly opening hooks adapted to engage opposite edges of the bed plate.

3. The combination with a pair of rails lying in intersecting planes and having gaps adjacent their intersecting point, of a rigid bed plate underlying the ends of said rails 110 adjacent the gaps, a rail section pivoted upon the top of the plate to swing in a horizontal plane, means whereby said rail section may be swung around its pivot, and laterally projecting guards on the opposite 115 ends of the pivoted rail section and adapted to have their terminals positioned adjacent the ends of said rails when said pivoted section is in operative position.

4. The combination with a pair of rails 120 lying in intersecting planes and having gaps adjacent their intersecting point, of a rigid bed plate underlying the ends of said rails

adjacent the gaps, a rail section pivoted upon the top of the plate to swing in a horizontal plane, means whereby said rail section may be swung around its pivot, and laterally projecting guard rods on the pivoted rail section and having their outer ends deflected upwardly and outwardly, for the purpose set forth.

In testimony whereof we have hereunto set our hands in presence of two subscribing 10 witnesses.

JAMES T. HAMILTON.
CHARLES C. McMULLEN.
